UNITED STATES PATENT OFFICE

RAY C. HITT, OF SEATTLE, WASHINGTON

PYROTECHNIC DISPLAY

Application filed November 13, 1931. Serial No. 574,895.

This invention relates to improvements in pyrotechnic displays and fireworks; and, more particularly, to a device designed to produce martial sounds generally associated 5 with the early spirit of '76.

The principal object is to produce first a piccolo effect, then the rat-tat-tat of the snare drum, and finally the boom of the bass drum. The representation of three marching figures, 10 one playing a fife or piccolo, the other two, drums, and known as the spirit of '76, have become so clearly associated with the 4th of July that I have deemed it desirable to reproduce by way of a firework these musical 15 sounds.

Another object of the invention is to produce these sounds in succession so that one blends into the other, and to have the sound producing device so arranged and connected 20 that a single lighting will suffice for all of the devices.

Other objects will be disclosed in the specification and claims forming a part of this application.

25 In the drawing:

Figure 1 is a top plan, partly broken away;

Figure 2 is a vertical section partly in elevation, taken on the line 2—2 of Figure 1;

Figure 3 is a horizontal section taken on 30 the line 3—3 of Figure 3; and

Figure 4 is a fragmentary horizontal section taken on line 4—4 of Figure 2 showing the fuse arrangement.

Referring to the drawing, in which similar parts are designated by like numerals:

Numeral 5 refers to a sound producing apparatus of the whistling type. This device in itself is not novel and may be of any one of several well known constructions. As shown, 40 an open-ended tube 5' is filled with a composition, such as potassium picrate, and packed therein. When ignited, the composition burns in the form of a series of very rapid explosions which sound to the ear like a 45 whistle, and, as the composition burns down the tube 5' the open space within the tube 5' is increased and the explosions sound like a whistle played in a descending chromatic scale. A fuse 6 contacts with the explosive 50 composition in the lower end of the open-

ended tube 5', and overlaps a fuse 7 of a number of small firecrackers 8 which are strung together in sequence, the overlapping of the fuse 7 by the fuse 6 occurring at 9 and 10 to insure the ignition at a plurality of points. 55 The fuse 6 after contacting the fuse 7 passes through an opening 11 formed in the top 11' of the container 12 to contact with the fuse 13 of a large firecracker 14 secured to the base 15 of the container 12. A reinforcing head member 18 of cardboard or other material is placed beneath the top 11' and has an opening 19 in alignment with the opening 11.

A collar 17, made of cardboard or other material, is placed around the base of the 65 whistling apparatus 5 and secured by glue or other adhesive material to the firecrackers 8. The collar 17 is so arranged that the ends of the firecrackers 8 extend beyond the outer periphery of the collar, the collar serving 70 to act as a stand for the whistling apparatus 5 and a sounding board for the firecrackers 8.

The top 11' corresponds to the head of a drum and the container 12 being hollow, adds 75 to the effectiveness of the same.

As actually used, the fuse 5 will be ignited and the whistling noise produced upon the ignition of the composition within the same. The fuse which passes from the whistling apparatus 5 will then ignite the fuse 7 of 80 the small firecrackers. It is to be noted that the fuse 6 overlaps the fuse 7 at several points so as to assure of the firecrackers 8 being ignited. These firecrackers, placed between the collar 17 and the top 11' with a 85 hollow chamber below, give the rat-tat-tat effect of a snare drum. The fuse 6 continues to burn and finally ignites the firecracker 14 in the bottom of the chamber so that the last noise confined in the chamber gives the impression of a bass drum, and at the same time, the force of this explosion will cause the container to be thrown up in the air, the whole effect being very attractive and unusual. 95

Having thus described my invention, what I claim is:

1. A pyrotechnic display comprising a hollow member having a top, means adjacent the top of the member for producing a plu- 100

rality of explosions, a covering over said means, said covering and hollow member adapted to affect the noise from the detonations.

5 2. A pyrotechnic display comprising a hollow member having a top, means adjacent the top of the member for producing a plurality of explosions, a covering extending intermediate the outer portion of the sound producing means, said covering and hollow member adapted to affect the noise from the detonations.

15 3. A pyrotechnic display comprising a hollow member having a top, a plurality of sound producing members arranged on said top, ignition means connecting said sound producing members in series, a covering extending over said sound producing members, said covering and hollow member adapted to affect the noise from the detonations.

25 4. A pyrotechnic display comprising a hollow member having a top, a plurality of sound producing members arranged on said top, means adapted to ignite said members connected in series, a collar extending over the said members, apparatus adapted to produce a whistling sound when ignited supported by said collar, means adapted to ignite said structure and contacting with said first mentioned means.

35 5. A pyrotechnic display comprising a hollow member having a top, a plurality of sound producing members arranged on said top, means adapted to ignite said members connected in series, a collar extending over the said members, apparatus adapted to produce a whistling sound when ignited supported by said collar, means adapted to ignite said structure and extending over and under said first mentioned means at a plurality of points to insure the ignition of said first mentioned means.

45 6. A pyrotechnic display comprising a hollow member having a top, a plurality of sound producing members arranged on said top, means adapted to ignite said members connected in series, a collar extending over the said members, apparatus adapted to produce a whistling sound when ignited supported by said collar, means adapted to ignite said structure and contacting with said first mentioned means and extending through said top into said hollow member, an explosive sound producing article within said hollow member, means for igniting said explosive member, said means contacting with the means extending into said hollow member.

55 In testimony whereof I affix my signature.
RAY C. HITT.
